CLAIM

I claim the ornamental design for a blade sharpening device,
as shown and described.

DESCRIPTION

FIG. 1 is a perspective view of a blade sharpening device embodying the new design, arranged proximate to a broken line depiction of a sharpening stone.

FIG. 2 is perspective view of the blade sharpening device with parts separated.

FIG. 3 is a front view of the blade sharpening device.

FIG. 4 is a back view of the blade sharpening device.

FIG. 5 is a first side view of the blade sharpening device.

FIG. 6 is a second view of the blade sharpening device.

FIG. 7 is a top view of the blade sharpening device; and,

FIG. 8 is a bottom view of the blade sharpening device. The broken and dashed lines in the drawings represent environmental subject matter and form no part of the claimed blade sharpening device design. The broken lines in FIG. 8 depict portions of the blade sharpening device in which the design is embodied that form no part of the claimed design.
